5 Sheets-Sheet 2

Fig. 2.

Fig. 12.

A cross-sectional view of a circular component, likely a bearing or seal. The outer ring is labeled 10. Inside the ring, there are several layers and components. Labels include: 12, 12, 12, 12, 12a, 13, 14, 14, 16, 17, 120, 121, and 123. The component features a central hub with a wavy pattern, surrounded by a thick outer ring. Internal segments are labeled 12, 12, 12, and 12a, with 12a being a smaller segment at the bottom. The label 13 is positioned between two segments. The label 14 is on the left and right sides, and 16 is at the bottom. The label 17 is at the very bottom center. The label 120 is on the right side, and 121 is on the far right. The label 123 is on the right side, just above 121. The label 10 is at the top.

PROCESS AND APPARATUS FOR SEPARATING MATERIALS

Nathan E. Joaquin, Los Angeles, Calif.

Application August 17, 1948, Serial No. 44,774

18 Claims. (Cl. 209—209)

The present invention relates to the separation of materials of different specific gravities. 15

An object of the invention is to obtain separation between two or more solid materials having different specific gravities, and the collection of all solids of substantially the same specific gravity at a single location, regardless of differences in physical sizes of the solids having the same specific gravity.

Another object of the invention is to obtain the simultaneous separation between solids of different specific gravities by allowing them to gravitate through water or other liquid, obtaining the deposition of all solids of the same specific gravity at the same point, regardless of differences in their physical size, such point or location being different from the point of deposition of solids of another specific gravity.

A further object of the invention is to provide an apparatus for classifying or separating solids, which is capable of precipitating the solids vertically through a liquid while moving them laterally through the liquid at a predetermined rate, to insure full vertical separation between solids of different specific gravities and separate deposition of solids of each gravity at particular points.

Still another object of the invention is to provide an apparatus for separating solids, which is capable of discharging the solids into a movable member submersible in water, or other liquid, and in which the point of discharge of the solids is variable, to insure vertical separation between solids of different specific gravities and the deposition or collection of all solids of the same gravity at a particular point.

Yet another object of the invention is to provide an apparatus for separating solids, in which solids of different physical sizes may be discharged into a movable member submersible in water, or other liquid, at spaced predetermined points, to cause vertical separation between solids of different specific gravities and collection of all solids of the same specific gravity at the same point, regardless of differences in their physical size. In this connection, the point of discharge of each physical size may be varied within close limitation.

A further object of the invention is to provide an apparatus for separating solids of different specific gravities, the separated solids being receivable in bins or containers that can be rearranged at selected intervals to insure dropping of the separated solids into particular containers, without danger of inadvertent commingling of the separated solids.

Still another object of the invention is to obtain the automatic removal of the separated solids from the individual containers in which they have been deposited.

Another object of the invention is to provide apparatus for hydraulically removing the separated solids from their individual containers in accordance with the level of the solids in each container.

Yet another object of the invention is to provide a movable member submersible in a liquid for separating solids by gravity, in which the member has a plurality of separated passages through which the solids gravitate, the passages having a predetermined shape to insure substantially uniform discharge of solids of the same specific gravity from the bottom or outlet end of each passage. In connection with this aspect of the invention, the passages may be made adjustable.

This invention possesses many other advantages, and has other objects which may be made more clearly apparent from a consideration of process described herein.

2

and several physical forms in which it may be embodied. Such forms are shown in the drawings accompanying and forming part of the present specification. These forms will now be described in detail, illustrating the general principles of the invention; but it is to be understood that such detailed description is not to be taken in a limiting sense, since the scope of the invention is best defined by the appended claims.

Referring to the drawings:

Fig. 10 is a longitudinal view, partly in section, of the hydraulic mechanism for effecting automatic discharge of the solids from a receiving bin;

Fig. 11 is a longitudinal section through a float controlled piston valve shown in Fig. 10; and

Fig. 12 is a modified form of vane and passage construction forming part of the rotor of the apparatus.

In connection with one aspect of the invention, it is desired to separate solids by effecting their gravitation through water, or other liquid, having a lesser specific gravity than all components of the solids themselves. The rate at which a solid particle will gravitate or precipitate through a liquid depends upon its size, shape and specific gravity. Thus, solids of the identical specific gravity, but of different physical size and shape, will gravitate through the liquid at different rates, and will reach a certain depth in the liquid at different times.

The present invention contemplates a process and apparatus for insuring that solids of the same specific gravity will reach the same collection point in the liquid, regardless of variations in their physical sizes and shapes.

In carrying out the process, the solids to be separated are classified in two stages. The first stage involves classification in accordance with various physical sizes, regardless of any differences in gravities. As an example, the mass of solids may be screened to effect their separation into batches of about ten mesh, twenty mesh, thirty mesh, etc. Each physical size of solid then undergoes the second stage of classification by allowing it to gravitate or precipitate in a liquid, such as water. During such precipitation through the water, a separation will take place between solids of different specific gravities. By causing lateral movement of the solids at a predetermined rate during their gravitation through the liquid, the separated solids of different gravities will reach the same depth at different times and at separated receiving points, where the individual solids of each gravity are collected.

A mass of solids of two or more different meshes or physical sizes may be caused to gravitate through the liquid simultaneously and solids of the same specific gravity will reach the same depth or receiving point as a result of their lateral motion through the liquid, provided that the points of discharge of the solids of different sizes into the liquid are spaced from one another accurately. Since solids of smaller physical size will require a longer time to descend a predetermined vertical distance through a liquid than particles of larger physical size, the former will be deposited into the liquid ahead of the latter. The spacing between the points of discharge into the liquid is so chosen as to insure that solids of the same specific gravity will descend through the liquid and will arrive at the same receiving point. Of course, the smaller size solid requires a longer time to descend through the liquid and

must be moved laterally a longer time and through a greater distance than the larger size solids.

By referring to the drawings, apparatus is disclosed for effecting separation of solids in accordance with their specific gravities, and regardless of differences in the physical sizes of the solids. The solids are caused to gravitate through water, or other suitable liquid, contained within a vertical cylindrical tank 10, suitably supported within a frame 11. This tank contains concentrate or receiving bins 12 in its lower portion, formed by an inner frusto-conical support 13 and by vertical radially extending partitions or baffles 14 running between the wall of the tank and the frusto-conical support. The partitions 14 may be placed at selected intervals depending upon the particular solids to be received therein.

Disposed above the receiving bins is a rotor 15 mounted for rotation about a vertical axis. This rotor is secured to a vertical shaft 16, whose lower end is rotatable in a bearing support 17 secured to the frusto-conical bin member 13. The upper end of the shaft is rotatably mounted in a bearing sleeve 18 fixed in a bearing support 19 suitably secured within the upper end of the frame 11.

The rotor 15 has a plurality of generally vertically arranged passages 20 that are submerged in the water in the tank, and through which the solids descend. These passages are formed by overlapping adjustable vanes 21, of generally U-shape, having overlapping peripheral or rim portions 22 secured to each other by top and bottom pivot screws 23, 24. The vanes also have inner portions 25 that overlap each other and are secured to the upper and lower hubs 26, 27 of the rotor by means of pivot screws 28, 29. The top pivot screws 23 passing through the peripheral portions 22 of the vanes are coaxial with the top pivot screws 28 passing through the inner flange portions 25 of the vanes. Similarly, the bottom pivot screws 24, 29 at the outer and inner portions 22, 25 of the vanes are coaxial with each other. The coaxial arrangement is provided to permit the vanes 21 to pivot upon one another without binding.

As stated above, the inner portions 25 of the vanes 21 are secured to the lower rotor hub 27, which is fixed to the rotor shaft 16 in any suitable manner, as by means of a cap screw 30 threaded through the hub and bearing against the shaft. The upper portions of the vanes 21 are secured to an adjustable rotor hub member 26 by the inner pivot screws 28, thus upper hub member being angularly movable about the shaft 16 in order to obtain the inclination from the vertical of the vanes 21. For purposes of obtaining such adjustment, a drive member 31 is secured to the shaft by one or more cap screws 32, and also by a key 33, this drive member having a lug 34 extending upwardly through an arcuate slot or opening 35 in the adjustable hub member 26. The latter has upwardly extending bosses 36 at opposite ends of its opening, through which adjusting screws 37 are threaded for bearing against the opposite ends of the lug 34.

By suitably turning the adjusting screws 37, the movable hub member 26 may be rotated with respect to the drive member 31 and shaft 16, such rotation also shifting the upper ends of the vanes 21 angularly with respect to the lower ends of the vanes. In this manner, the vanes are angled to the vertical, with their upper ends placed ahead of their lower ends in the direction of rotation of the rotor 15. Following the adjustment of the vanes 21 to the required degree, they are held in such adjusted position by tightening lock nuts 38 on the adjusting screws 37 against the bosses 36.

The inner pivot screws 28, 29 pass freely through holes in the inner vane flanges 25, and are bottomed in threaded holes 39 in the hubs 26, 27. Similarly, the outer pivot screws 23, 24 pass freely through holes in the outer rim portion 22 of each vane, being threaded into the rim portion of an adjacent vane. Such arrangement of the screws, coupled with their coaxiality, allows the vanes 21 to rock or pivot on the screws and be moved to the desired positions of adjustment.

The rotor is rotated by a suitable motor 40, which drives a variable ratio transmission 41, of suitable construction, connected to a drive shaft 42 mounted within a bearing bracket 43 fixed to the frame 11. A bevel pinion 44 is attached to this drive shaft 42 and meshes

with a bevel gear 45 secured to the rotor shaft 16. By means of this drive mechanism, the rotor 15 is rotated at the desired speed, which can be varied by changing the transmission ratio of the variable speed device 41, depending upon the solids to be separated in the apparatus.

The rotor 15 is disposed in the tank 10, which is filled with water, or other suitable liquid. The level of the water is preferably above the upper ends of the adjustable vanes 21, the height of the water being determined by an overflow pipe 46 extending into the tank. The solids to be separated in accordance with their specific gravities are placed in one or more feed chutes 47 extending radially of the drum with their outlet ends disposed over the passages 20. Each feed chute 47 is adjustable with respect to the receiving bins 12 to insure that solids of the desired gravity will drop through the liquid in the tank into the proper bin. Such adjustment is made circumferentially of the liquid tank. In addition, the outlet area or size of the feed chute 47 may be varied, depending upon the type of material to be separated in the apparatus.

The foregoing adjustable features may be provided by forming each feed chute 47 with spaced inner and outer end walls 48, 49, with a fixed side wall 50 interconnecting the end walls, and with an opposed movable side wall 51 pivotally mounted to the upper ends of the end walls by pins 52 or the like (see Figs. 4 to 7, inc.). The side walls 50, 51 taper downwardly toward each other to provide a generally rectangularly shaped outlet 53 of smaller size than the inlet or upper end of the chute.

The size of the outlet opening 53 can be varied by moving the adjustable side wall 51 to and from the fixed side wall 50. To accomplish this purpose, an adjusting screw 54 is threaded through a central boss 55 in the movable wall, the end of the screw engaging the inner surface of the fixed wall 50. Spaced screws 56 are disposed on opposite sides of the adjusting screw 54, passing freely through holes 57 in the movable wall 51 and threaded through bosses 58 in the fixed wall 50. By turning the central screw 54, the movable wall 51 may be swung on its coaxial pivot pins 52 to and from the fixed wall 50, to vary the size of the outlet chute opening 53. When such adjustment has occurred, the other screws 56 are tightened in order to hold the adjusting screw 54 firmly against the fixed wall 50, and secure the movable wall 51 to the remainder of the chute device.

One or more feed chutes 47 may be disposed around the tank 10 and above the rotor 15. Inner and outer shafts or trunnions 59, 60 are fixed to the inner and outer walls 48, 49 of each feed chute, the inner trunnion 59 resting upon a horizontal stationary plate or disc 61 fixed to the bearing sleeve 18 for the rotor shaft 16. The outer trunnion 60 is adjustably mounted within a bracket 62 having depending legs 63 straddling the upper end of the tank 10.

The feed chute 47 may be disposed radially at selected points around the tank 10, and, when disposed at the proper location, is maintained in such position by pins 64 on opposite sides of the inner trunnion 59 received within holes 65 in the stationary plate 61, as well as by clamping the bracket 62 to the tank by a suitable lock screw 66 threaded through one of the bracket legs 63 and bearing against the exterior of the tank. It is to be noted that the holes 65 in the stationary plate 61 are disposed on a circle, and that each lock screw 66 may be loosened to permit circumferential adjustment of each feed chute around the tank 10 and stationary plate; after which the pins 64 are inserted in the plate 61 on opposite sides of the inner trunnion 59 and the bracket 62 affixed to the tank by the lock screw 66.

Each feed chute 47 may be adjusted with respect to the receiving bins and the rotor comparatively coarsely in the manner just described. A finer adjustment of the position of the feed chute 47 and particularly its outlet 53 can be made by rotating the feed chute about the axis of its trunnions 59, 60.

The outer trunnion 60 extends through a split portion of the bracket 62, and has an index pointer 67 attached to it, which is movable over suitable indicia 68 on the exterior of the bracket. A cap screw 69 extends through the split portion of the bracket, and, when tightened, serves to clamp the outer trunnion 60 firmly to the bracket.

When a fine adjustment is desired of the outlet end 53 of the feed chute 47, the cap screw 69 is loosened, which permits the outer trunnion 60 to be rotated in the bracket 62 to the desired degree, the extent of the angular movement being indicated by the pointer 67. Thereafter, the cap screw 69 is tightened to hold the feed chute 47 in its adjusted position.

Each feed chute receives solids of a particular mesh from suitable apparatus capable of separating such solids into different physical sizes. As disclosed in the drawings, the mass of solids may be first disposed within a first shaker screen 70 of suitable construction and of suitable mesh. The solids that do not pass through this screen are fed through a suitable passage or tube 71 to one of the feed chutes 47. Solids that are capable of passing through the upper screen 70 then move onto a lower screen 72, where solids of a smaller mesh come to rest and through which solids of a still smaller mesh may pass onto a third screen 73.

As many screens are provided as are necessary to separate the material into different physical sizes or meshes. As indicated above, the large mesh material is conducted through a suitable passage 71 to one of the feed chutes 47. The other smaller size materials are conducted through individual passages or tubes 74, 75 to other individual feed chutes 47. The solids are caused to move from each shaker screen into each conveyor tube in any suitable manner, as by gravity, in view of the inclined disposition of the shaker screens 70, 72, 73.

As above stated, solids of larger physical size will gravitate through the liquid in the tank at a faster rate than solids of smaller physical size. Accordingly, the solids of largest physical size are directed into a feed chute 47 that is mounted in the apparatus in advance of the other feed chutes, as regards the direction of rotation of the rotor 15. Solids of the next physical size are conveyed to a feed chute behind the one just mentioned, and this feed chute is ahead of the feed chute of the solids of still smaller physical size.

The number of feed chutes and their relative arrangement around the apparatus will depend upon the material to be separated and the location of the different receiving bins 12 in the lower part of the tank 10. Each receiving bin 12 is disposed ahead of the feed chute from which it is to receive solids, in order that rotation of the rotor 15 will bring the different separated materials to the right bin at precisely the right time.

The performance of a separating operation may perhaps be better understood by referring to the diagrammatic view shown in Fig. 2. Solids of one physical size are contained in one feed chute 47a at the point A, and solids of another and greater physical size are contained in the feed chute 47b at point B. Let it be assumed that the rotor 15 is advancing in the direction of the arrow C and that it is desired to have all solids of one particular gravity drop into a stationary bin at the point D, whereas solids of another lighter gravity are to drop into the adjacent receiving bin at the point E.

The smaller size material discharges from the feed chute 47a, located at the point A, into one of the vertical passages 20 formed by the rotor vanes 21. This material begins settling through the passage during rotation or movement of the passage in the direction of the arrow C. During the settling action, the solids e, f, g of different specific gravities that were in the feed chute 47a will separate in accordance with their specific gravities, and may become separated by certain distances. The solids e of the greatest specific gravity will reach the end of the passage 20 when the latter has been moved into alignment with the receiving bin at station D. During the time that the drum continues its rotation from the bin D to the bin E, solids f of lighter specific gravity are settling through the passage 20 to its bottom end, dropping into the bin at E when the passage becomes aligned therewith. In like manner, still lighter solids g will drop into the next succeeding bins during rotation of the rotor 15.

Referring still to Fig. 2, solids h, j, k are also dropping out of another feed chute 47b at the point B into another passage 20a which is then closer to the receiving bins D and E than passage 20 when it is disposed under chute 47a. These solids h, j, k are of larger physical size than those in the feed chute 47a at point A and will drop through the water in

the passage 20a at a faster rate, the solids h, j, k separating from one another in accordance with their specific gravities. When the drum or rotor 15 is rotated to bring the passage 20a into alignment with the receiving bin at the point D, the solids h of greatest specific gravity (same gravity as solids e) will drop into the bin D, and as rotation of the rotor continues, solids j, k of progressively lesser specific gravity will drop into the bin E and the succeeding bins.

Thus, by appropriate positioning of the feed chutes 47 with respect to the receiving bins 12, it is possible to obtain separation of the solids in accordance with their specific gravities, and the dropping of all solids of the same specific gravity into the same receiving bin, regardless of their physical size.

It is to be noted that the outlet 53 of each feed chute 47 is preferably of substantially lesser width than the width of each passage 20. This proportioning of parts is desired to insure a closer timed relation between the point of discharge of the solids into each passage and the depositing of the separated solids into the receiving bin. The making of the discharge opening 53 relatively narrow causes the discharge to occur substantially along a radial line at the same lateral distance from the receiving bins 12. This prevents the solids from entering the passages 20 simultaneously along a substantial arcuate extent and at varying distances from the bins 12. This latter condition might result in some solids of a particular gravity dropping from a passage before or after it has become aligned with its receiving bin.

Since the rotor 15 is moving during discharge of the solids into each passage 20, the solids will enter the leading passage side ahead of the trailing side, and will begin descending through the water at different vertical distances. To offset this occurrence, the blades or vanes 21 are inclined, as described above, with the upper ends of the vanes disposed forwardly of their lower ends. The particles engage the inclined forward vane of a passage 20 confining them, and move downwardly along such inclined vane, being retarded by the latter. This retarding action allows the trailing portion of the solids of each specific gravity to catch up to the leading portions. As a matter of fact, the proper inclination of the vanes 21 will cause solids of the same specific gravity in a passage 20 to reach a receiving bin 12 in almost a horizontal plane, insuring the proper discharge of such solids into the receiving bin before the passage has moved from alignment with such bin.

A modified form of passage is disclosed in Fig. 12, in which the vanes 80 defining the sides of the passage are not helically disposed or angled. Instead, these vanes are disposed radially of the rotor axis, the leading vane having an inclined baffle 81 secured to it, with the baffle inclined downwardly in a trailing direction as regards the rotary direction of the rotor 15. This inclined baffle not only serves to retard the descent of the leading portions of the solids entering the passage, but it also provides a confined outlet 82a from the passage, which is relatively narrow along a radial line; so as to insure the discharge of the solids of the same specific gravity into the desired receiving bin. The width of the passage outlet 82a is substantially less than the width of the bin 12, allowing ample time for the solids of a particular specific gravity to drop out of the passage during the sweep of the latter across the stationary bin.

As the solids accumulate in each bin 12 to a specified height, they are removed automatically by hydraulic devices (see Figs. 1, 10, and 11). Each bin 12 has an outlet 82 communicating with its lower portion that is normally closed by a valve head 83 containing a seal ring 84 adapted to engage a seat 85 provided by the outer end of the outlet. Water from a suitable supply line 86 flows through a pipe 87 into a line 88 communicating with the interior of a valve housing 89. This housing has a nozzle 90 slidable therein containing a central fluid passage 91 and radial ports 92 leading therefrom adapted to communicate with the jet line 88. A jet or orifice 93 is threaded into the nozzle member 90, and may have a restricted passage 94 through which water under relatively high velocity can be jetted or forced into the receiving bin 12.

When the nozzle 90 is in its inward position toward the water tank 10, as disclosed in Fig. 10, its radial passages 92 are located between seal rings 95, 96 in the valve housing, preventing communication between the jet line 88 and the central passage 91 through the nozzle, so that water cannot flow through the jet 93 into the receiving bin 12. With the nozzle in this position, the valve head 83 mounted on its outer end is forced against the valve seat 85 to close the outlet 82 from the bin. When, however, the nozzle 90 is shifted to the left, as seen in Fig. 10, the valve head 83 is moved away from its cooperator seat 85 on the outlet, and, at the same time, the nozzle ports 92 are placed between the seal rings 96, 97 on opposite sides of the jet line 88, which allows water under pressure to flow into the nozzle 90 and out of the jet 93, the jet acting upon the concentrate or solids in the bin 12 and flushing them through the outlet 82 into a suitable container (not shown).

The closed or open position of the nozzle 90 is dependent upon the level of the concentrate or solids in the bin. As the height of the concentrate rises in the bin, it elevates a density float 98, which is connected to a rod 99 extended through a vertical guide 100 secured to a bracket 101 clamped to the upper end of the tank 10 by a lock screw 102. The upper end of the rod 99 is fixed to a head 103 that is pin connected to a lever 104 mounted upon a fulcrum pin 105 on the bracket. The other end of the lever has a pin 106 riding within a transverse slot 107 in a slide or piston valve 108 slidable within a valve housing 109.

At one side of the valve housing 109 are outer exhaust lines 110, 111 and an intermediate water supply line 112, which is connected to the main water supply line 86. The other side of the housing 109 has a pipe or line 113 connected to one side of a housing 114 containing a diaphragm 115 secured to the nozzle 90, the marginal portion of the diaphragm being clamped to the housing. Another line 116 runs from the valve housing 109 and communicates with the diaphragm housing 114 on the opposite side of the diaphragm 115.

As shown in the drawings, as the density float 98 moves upward, the slide valve 108 moves downwardly, and vice versa, because of the lever interconnection 104. As shown in Fig. 11, the slide valve 108 is in its upper position, and the seal rings 117, 118, 119 mounted thereon are so disposed relative to the various lines entering the valve body 109 as to exhaust the line 113 communicating with the inner end of the diaphragm 115 and allow water under pressure to flow into the other line 116, which shifts the diaphragm inwardly and places the nozzle 90 out of communication with the jet line 88, closing the bin outlet 82. As the float 98 rises with accumulation of concentrate in a bin, the valve 108 is shifted downwardly, exhausting line 116 and placing line 113 in communication with water line 112. Water pressure now acts on the inner side of the diaphragm 115, shifting the nozzle 90 to the left (Fig. 10) and placing its passage in communication with the jet line 88. Such shifting also moves the head 83 from the bin outlet 82. Water can now jet through the outlet into the bin and flush concentrate from the bin through its outlet 82.

During removal of the concentrate the float 98 drops, and effects upward shifting of valve member 108 to its original position. This causes shifting of the diaphragm 115 in the other direction, or to the right, as seen in Fig. 10, urging the valve head 83 against its seat 85, to close the jet outlet 82, and shifting the nozzle ports 92 between the seal rings 95, 96, which prevents flow of water from the jet line 88 through the nozzle 90.

It is apparent that the concentrates are automatically removed from the bin 12 by hydraulic means. It is to be understood that there is a nozzle control valve and float for each bin, although only one is disclosed in the drawings for simplicity of illustration.

The partitions or baffles 14 for the bins 12 are placed at selected intervals around the bottom end of the rotor 15. The bins for receiving the concentrates of different specific gravity preferably do not extend around the entire periphery of the rotor, there being a large bin 12a for the usual gangue.

The water in the passages 20 is relatively quiescent although a slight movement is created by settling of the solids through the water in the rotor passages. During such settling, some particles of extremely small size may remain in colloidal suspension and will not drop from the

passage. After essentially all solids have dropped from a passage 20, the latter will be rotated over a spray line 120 that may be disposed radially of the rotor 15. This spray line creates upwardly directed currents of fresh water, which tend to clear the passages 20 of the colloidal suspensions. The excess water flows out of the tank 10 through the overflow pipe 46. The spray line or purging line 120 is connected with the water supply 86, 87, the flow through it being controlled by a suitable valve 121.

In order to prevent any agitation, caused by the spray line or nozzle 120, in the water within the passages 20 from effecting an agitation of the relative quiescent water in the other passages through which solids are settling, a water damper 122 is provided adjacent the upper end of the rotor 15. This damper is suitably supported from the stationary plate 61, with its lower end arranged radially of the rotor and immediately adjacent the upper ends of the vanes 21. It acts as a barrier, to dampen the currents of ascending water and prevents such currents from having any substantial disquieting effects on the water in the passages containing solid materials.

In lieu of using the spray line 120 extending radially of the rotor 15 for removing colloids, a curved spray line 123 may be disposed in the water tank 10 immediately below the outside of the periphery of the rotor 15. This spray line may be connected to the water supply line 86, 87 through a valve 124 and serves to send water upwardly along the rotor, which will have some effect in causing the colloidal suspensions to rise in the passages 20 and pass out through the overflow line 46, without setting up substantial ascending currents that might disquiet the water in the other passages through which solids are descending. The water emanating from the curved spray line 123 will dilute the water in the tank 10, and, in view of the oversupply of water in the latter, cause some of the colloids to flow through the overflow line 46 with the excess water.

The inventor claims:

1. The process of classifying solids; which comprises separating said solids into various physical sizes; vertically precipitating solids of smaller size through a liquid while moving said smaller size solids laterally through said liquid from a starting point toward a collection point; simultaneously vertically precipitating solids of larger size through said liquid while moving said larger size solids laterally toward said collection point from a starting point in advance of said first mentioned starting point; said starting points being so chosen with respect to each other and said collection point that solids of the same specific gravity and different sizes will be deposited at said same collection point.

2. The process of classifying solids; which comprises vertically precipitating solids of smaller size through a liquid while moving said smaller size solids laterally through said liquid from a starting point toward a collection point; simultaneously vertically precipitating solids of larger size through said liquid while moving said larger size solids laterally toward said collection point from a starting point in advance of said first-mentioned starting point; said starting points being so chosen with respect to each other and said collection point that solids of the same specific gravity and different sizes will be deposited at said same collection point.

3. In apparatus for classifying solids: means for separating said solids into various physical sizes; a tank adapted to contain a liquid; a rotor rotatable in said tank while substantially submerged in said liquid, said rotor having generally vertical passages; and means for conducting solids of one physical size from said separating means to one point of discharge into one or more of said rotor passages, and solids of another physical size from said separating means to another point of discharge into one or more of said rotor passages; the points of discharge being below the surface of the liquid.

4. In apparatus for classifying solids: a tank adapted to contain a liquid; a member movable in said tank while substantially submerged in said liquid and having a plurality of generally vertical passages; the forward faces of said passages being inclined, with the upper end of each forward face disposed ahead of its lower end; and means for discharging solids into the upper ends of said passages.

5. In apparatus for classifying solids: a tank adapted to contain a liquid; a rotor rotatable in said tank while substantially submerged in said liquid and having a plurality of generally radial and vertical passages; the for-

ward faces of said passages being inclined, with the upper end of each forward face disposed ahead of its lower end; and means for discharging solids into the upper ends of said passages.

6. In apparatus for classifying solids: a tank adapted to contain a liquid; a rotor rotatable in said tank while substantially submerged in said liquid and having a plurality of generally radial and vertical passages; the forward faces of said passages being inclined, with the upper end of each forward face disposed ahead of its lower end, the lower end of each passage being of less cross-sectional area than its upper end; and means for discharging solids into the upper ends of said passages.

7. In apparatus for classifying solids: a tank adapted to contain a liquid; a member movable in said tank while submerged in said liquid and having a plurality of generally vertical passages, each passage converging in a downward direction; the forward faces of said passages being inclined, with the upper end of each forward face disposed ahead of its lower end; and means for discharging solids into the upper ends of said passages.

8. In apparatus for classifying solids: a tank adapted to contain a liquid; a member movable in said tank while substantially submerged in said liquid, said member comprising supporting means, vanes mounted on said supporting means to define generally vertical passages; and means for adjusting said vanes on said supporting means to vary the inclination of said vanes to the vertical.

9. In apparatus for classifying solids: a tank adapted to contain a liquid; a rotor rotatable in said tank while substantially submerged in said liquid, said rotor comprising supporting means, generally radial vanes mounted on said supporting means and overlapping each other to define generally vertical passages; and means for adjusting said vanes on said supporting means to vary the inclination of said vanes to the vertical.

10. In apparatus for classifying solids: a tank adapted to contain a liquid; a rotor rotatable in said tank while substantially submerged in said liquid, said rotor comprising generally radial vanes spaced from each other to define generally vertical passages, and an inclined generally radial baffle in each passage extending from the upper end of one vane to a point adjacent the lower end of another vane, to form a restricted outlet at the lower end of each passage.

11. In apparatus for classifying solids: a tank adapted to contain a liquid; a rotor rotatable in said tank while substantially submerged in said liquid, said rotor comprising generally radial vanes spaced from each other to define generally vertical passages, and an inclined generally radial baffle in each passage extending to a point adjacent the lower end of another vane, to form a restricted outlet at the lower end of each passage.

12. In apparatus for classifying solids: a tank adapted to contain a liquid; a member movable in said tank while substantially submerged in said liquid and having a plurality of generally vertical passages; at least a portion of the forward faces of said passages being inclined in such manner that the upper end of the inclined portion is forward of the lower end of said inclined portion; and means for discharging solids into the upper ends of said passages.

13. In apparatus for classifying solids: a tank adapted to contain a liquid; a rotor rotatable in said tank while substantially submerged in said liquid and having a plurality of generally radial and vertical passages; at least a portion of the forward faces of said passages being inclined, with the upper end of each forward face disposed ahead of its lower end; and means for discharging solids into the upper ends of said passages.

14. The process of classifying solids, which comprises: separating the solids according to size; laterally moving substantially vertical columns of liquid; and simultaneously depositing the solids in accordance with their size at laterally spaced points along the lateral path of movement, so that solids of different sizes and the same specific gravity are discharged at a common point from the columns.

15. The process of classifying solids, which comprises: separating the solids according to size; laterally moving substantially vertical columns of liquid; simultaneously depositing the solids in accordance with their size at laterally spaced points along the lateral path of movement, so that solids of different sizes and the same specific gravity are discharged at a common point from the columns; and separately collecting solids in groups of different specific gravities.

16. The method of separating granular materials which comprises leading relatively small batches of material to be separated into an isolated column of liquid in progressively increasing size groups, allowing said batches to settle together through said column, and collecting the material consecutively as it passes the end of said column.

17. The method of separating granular materials which comprises leading relatively small batches of material of progressively increasing size groups successively into an isolated column of liquid, allowing the material of all of said batches to settle together through the column, and collecting the material consecutively as it settles past the end of the column.

18. The method of separating granular materials which comprises putting batches of material into an isolated column of liquid in progressively increasing size groups and in superposed relation, allowing said batches to settle together through said column, and collecting the material consecutively as it passes the bottom of said column.
